DESIGN FOR A PIN OR SIMILAR ARTICLE

Arthur Gerald Leary, Mount Vernon, N. Y.

Application June 2, 1944, Serial No. 113,838

Term of patent 3½ years

(Cl. D45—19)

To all whom it may concern:

Be it known that I, Arthur Gerald Leary, a subject of the King of Great Britain, and resident of Mount Vernon, in the county of Westchester and State of New York, have invented a new, original, and ornamental Design for Pin or Similar Article, of which the following is a specification, reference being had to the accompanying drawing, forming a part thereof.

Fig. 1 is a top plan view of a pin or similar article embodying the design, and

Fig. 2 is an edge view of the pin or similar article looking from the bottom of Fig. 1.

The pin or similar article may be provided with suitable means for attachment, as to a garment of the wearer, a conventional form of such attaching means being shown in broken lines.

I claim:

The ornamental design for a pin or similar article, substantially as shown and described.

ARTHUR GERALD LEARY.
